United States Patent

Des. 235,447
Patented June 17, 1975

235,447

FREESTANDING FIREPLACE

Paul H. Lever, P.O. Box 1289,
Fallbrook, Calif. 92028

Filed Dec. 6, 1973, Ser. No. 422,279

Term of patent 14 years

Int. Cl. D23—03

U.S. Cl. D23—97

FIG. 1

FIG. 7

FIG. 3

FIG. 5

FIG. 2

FIG. 6

FIG. 4

FIG. 1 is a perspective view of a fireplace enclosure embodying my design;

FIG. 2 is a front view thereof;

FIG. 3 is a top view thereof;

FIG. 4 is a bottom view thereof;

FIG. 5 is a left side view thereof;

FIG. 6 is a right side view thereof; and

FIG. 7 is a rear view thereof.

The cross-line shading in FIGS. 1, 2, 3, 5 and 6 representing conventional screening is understood to repeat uniformly throughout the areas of the screen member.

I claim:

The ornamental design for a freestanding fireplace, substantially as shown and described.
